PRINTER'S REGISTERING DEVICE

Elmer F. Noell, Cincinnati, Ohio, assignor to The
Printing Machinery Company, Cincinnati,
Ohio, a corporation of Ohio

Application May 31, 1929. Serial No. 367,389

8 Claims. (Cl. 101—387)

My invention relates broadly to drop-in registering devices for printers' use, with which printing plates may be held in registered position in a foundation support having dovetailed grooves 5 therein.

In a co-pending application Serial No. 351,049, filed March 29, 1929, I have disclosed a registering device in which parts of the body of a drop-in hook are so formed that one side of the body 10 may be aligned with one side wall of a dovetail groove, and another side of the body may be aligned with the opposite wall of the groove. It is an object of my invention to provide in the broad type of device disclosed in this co-pending 15 application for cooperating members one having a wall which will register with one wall of a foundation plate groove, and another having a wall which will register with the opposite wall of the groove, which members will occupy a minimum of length within the groove so that the 20 devices may be positioned as close together as is necessary.

Another object is the provision of a registering device in which the device may be inserted on a 25 key and then positioned within a mounting groove without other manipulations being necessary than the turning of the key which guides the device into the groove and also clamps it within the groove.

Specifically it is an object of my invention to provide a clamping jaw having an adjustment screw having a shoulder seated against an annular flange surrounding an aperture in the jaw, and with the threaded part of the screw adjustably retaining a clamping block member 30 which is held in spaced position for a cooperating block member.

The above and other objects to which reference will be made in the ensuing disclosure I accomplish by that certain combination and arrangement of parts of which I have shown a preferred embodiment.

In the drawing:—

Figure 1 is a plan view of a foundation plate 45 having grooves with four of the registering devices retaining a printing plate on the foundation member.

Figure 2 is an end elevation of the registering device.

Figure 3 is a side elevation of the device.

Figure 4 is a side elevation of the device shown from the side opposite from that indicated in Figure 3.

Figure 5 is a sectional view taken along the 55 lines 5—5 in Figure 1.

Figure 6 is a sectional view of a slightly modified type of device.

The foundation plate 1 is provided with a series of spaced grooves 2 which are dovetailed as indicated. The side walls 3 of the grooves are 60 inclined outwardly from top to bottom so that when a drop-in hook is once within the groove, it may be readily clamped or locked within the groove by either pushing upwardly on the body 65 of the device or securing a relative movement between the under surface of the jaw and the wedging members.

A printing plate is indicated at 4 and I have indicated four clamps as employed to hold the printing plate in position.

The registering device consists of the usual pivoted jaw member having an inclined clamping face 5 which engages the inclined edge 6 of the printing plate. The jaw also has what might be termed a back portion 7. The jaw has an 75 aperture 8 therein and formed around this aperture is an annular flange 9 against which the under surface of the head 10 of an adjustment screw seats. The adjustment screw is made available for adjustment with a key by having an internal squared portion 11 and an aperture 12 in the screw to allow for the insertion of the key into the squared portion.

The threads 13 of the screw engage the threads 14a of a lower clamping block member 14. The 85 member 14 has tracks 15 extending in alignment with grooves 16 in an upper clamping block member 17. Relative movement of the two clamping blocks toward the clamping jaw widens out the 90 distance between the face 18 of block member 17 and the face 19 of block member 14. This is because the direction of the tracks and grooves corresponds to one of the slanting faces. The face 18 bears against one wall of a foundation plate 95 groove and the face 19 bears against the opposite wall.

There is a thin plate 20 mounted on the side of the block 17 adjacent the under surface of the clamping jaw. This plate has an aperture therein which embraces an annular groove 21 in the neck of the screw. As a modification of this method of causing relative movement of the two block members, I may also or instead provide springs such as are indicated at 22 in Figure 6 which maintain the spacing of the blocks.

To insert the device the key is inserted in the hole in the screw and the screw is rotated until the blocks are far enough apart to allow for insertion within a groove. The key is then turned clockwise, as indicated in the figures, and the 110

block members are thus wedged within the groove. It is preferable to have the aligning tracks inclined, as otherwise the faces of the blocks would remain the same.

5 While I have only disclosed one specific type of drop-in hook embodying my invention, modifications in the particular arrangement for aligning the clamping members will occur to others skilled in the art, but insofar as such modified 10 structures incorporate the mechanical principle involved, I consider the same within the scope of my invention.

Having thus described my invention, what I claim as new and desire to secure by Letters Patent, is:—

15 1. A printers' registering device of the character specified comprising in combination with a clamping jaw, relatively movable wedging and clamping members for insertion within a groove 20 of a foundation support, said members being provided with interconnecting guiding means for restricting the relative movement of said members to a plane inclined to the face of the support, and means for maintaining the spacing of said members.

25 2. In a device of the character specified, a jaw member having an aperture therein, wedging and clamping members, a screw extending within said aperture, one of said wedging members having a threaded aperture to seat said screw, and means for maintaining said wedging and clamping members in spaced relation.

30 3. In a device of the character specified, a jaw member having an aperture therein, wedging and clamping members, a screw extending within said aperture, one of said wedging members having a threaded aperture to seat said screw, and means for maintaining said wedging and clamping members in spaced relation, and means for guiding one of said members in a plane inclined relative to said other member.

35 4. A printers' registering device having a jaw and clamping wedge members, a screw for causing relative movement of said members, said screw provided with means to receive a key, and means for adjusting the relative position of said members to reduce the combined width of said members so that they may be inserted within a foundation plate dovetailed groove, and means for maintaining said members in spaced relative position.

40 5. In a printers' registering device, a plate clamping jaw, a pair of wedging members below the jaw, and a screw threaded into one member and rotatable in and bearing down on the jaw, said one member having wedging contact under the other member whereby the members are

caused to expand or permitted to contract transversely as the screw is turned one way or the other, said members being shaped to wedge under the undercut sides of a groove in a plate support when expanded, and to permit their withdrawal from the groove when contracted, and means causing said other member and the jaw to follow the axial movement of the screw for contraction.

55 6. In a printers' registering device, a plate clamping jaw, a pair of wedging members below the jaw, a screw threaded into one member and rotatable in and bearing down on the jaw, said one member having wedging contact under the other member whereby the members are caused to expand or permitted to contract transversely as the screw is turned one way or the other, said members being shaped to wedge under the undercut sides of a groove in a plate support when expanded, and to permit their withdrawal from the groove when contracted, and having mutually 95 engaging means guiding their relative movement for contraction, and means causing said other member and the jaw to follow the axial movement of the screw for contraction.

7. In a printers' registering device, a plate clamping jaw, a pair of wedging members below the jaw, and a screw threaded into one member and limiting separation of the jaw and the other member axially of the screw but permitting rotation of the jaw relative to the two members and 105 to the screw, said one member having wedging contact under the other member whereby the members are caused to expand or permitted to contract transversely as said screw is turned one way or the other, said members being shaped to 110 wedge under the undercut sides of a groove in a plate support when expanded, and to permit their withdrawal from the groove when contracted.

8. In a printers' registering device, a plate clamping jaw, a pair of wedging members below the jaw, and a screw threaded into one member and limiting separation of the jaw and the other member axially of the screw but permitting their rotation relative to each other and to the screw, said one member having wedging contact under 120 the other member whereby the members are caused to expand or permitted to contract transversely as said screw is turned one way or the other, said members being shaped to wedge under the undercut sides of a groove in a plate support 125 when expanded, and to permit their withdrawal from the groove when contracted, and having mutually engaging means holding them together and guiding their relative movement for contraction.
